[57] CLAIM

The ornamental design for a key for an electric lock, as shown and described.

DESCRIPTION

FIG. 1 is a front perspective view of the key for an electric lock showing my new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof; and
FIG. 8 is a right side elevational view thereof, the broken-line depiction of a female electrical receptor being for illustrative purposes only and forming no part of the claimed design.

FIG. 1**FIG. 2****FIG. 3****FIG. 4****FIG. 5****FIG. 6****FIG. 7****FIG. 8**
